CEMENT AND CONCRETE PLACER

Robert O. Howard, Redding, Calif.

Application August 20, 1940, Serial No. 353,432

10 Claims. (Cl. 91—45)

This invention relates to a compressed air operated placer for cement and concrete, and is designed primarily for placing cement and concrete behind forms, but it is to be understood that a placer, in accordance with this invention is for employment in any connection for which it may be found applicable.

A cement and concrete placer, in accordance with this invention, is of the gun type.

The invention aims to provide, in a manner as hereinafter set forth, a placer for the purpose set forth, whereby it will eliminate the slumping of the placed material, more particularly concrete and which is very advantageous from a saving standpoint in that it requires less cement to be placed with the aggregate.

The invention further aims to provide, in a manner as hereinafter set forth, a placer for the purpose referred to in that it provides for the expeditious placing of concrete in a more economical and effective manner than heretofore.

The invention further aims to provide, in a manner as hereinafter set forth, a placer for the purpose set forth including a plurality of superposed compressed air discharge nozzles capable of being selectively or simultaneously made active.

The invention further aims to provide, in a manner as hereinafter set forth, a compressed air operated placer of the gun type including a lengthwise bodily adjustable compressed air directing nozzle capable of being pushed forward toward or drawn back in relation to the discharge mouth of the gun to meet the convenience of the operator, and further to facilitate the placing of air behind the material to be expelled and placed.

The invention further aims to provide, in a manner as hereinafter set forth, a compressed air operated placer of the gun type including upper superposed compressed air directing elements or nozzles so disposed whereby any material adhering to the inner faces of the sides of the hopper may be forced downwardly to a position to be expelled.

The invention further aims to provide, in a manner as hereinafter referred to, a placer for the purpose set forth including a hopper for receiving the material to be placed having a material intake, and a controllable compressed air operated closure gate for said intake.

The invention further aims to provide, in a manner as hereinafter set forth, a placer of the type referred to including in combination a hop-

per for receiving plastic material and fluid means for discharging the material from the hopper.

The invention further aims to provide, in a manner as hereinafter set forth, a placer for the purpose set forth including a hopper for receiving plastic material and fluid means directed at different levels for removing the material adhering to the sides of the hopper, and fluid means disposed at a lower level for discharging the material from the hopper.

The invention further aims to provide, in a manner as hereinafter set forth, a controllable compressed air operated placer for the purpose set forth which is simple in its construction and arrangement, strong, durable, compact, thoroughly efficient in its use, readily assembled, conveniently controlled, and comparatively inexpensive to construct.

Embodying the aims aforesaid and others which may hereinafter appear, the invention consists of the novel construction, combination and arrangement of parts, as will be more specifically described and illustrated in the accompanying drawings, wherein is shown an embodiment of the invention, but it is to be understood that changes, variations and modifications may be resorted to which fall within the scope of the invention as claimed.

In the drawings:

- 30 Figure 1 is a side elevation of the placer.
- Figure 2 is a top plan view of the placer with the slide gate or closure thereof partly opened.
- Figure 3 is a section on line 3—3 of Figure 1.
- Figure 4 is a section on line 4—4 Figure 3, and
- 35 Figure 5 is a sectional detail upon an enlarged scale.

The placer includes a hopper 5 which receives the material which is to be placed. The hopper which is of substantially rectangular contour in plan comprises a top wall 6 formed with a controllable entrance or intake opening 7, of rectangular contour for the passage of the material into the hopper which is to be placed, a pair of oppositely disposed side walls 8, 9 of like form, a rear wall 10, a front wall 11 and a bottom wall 12. Each of the side walls including a vertically disposed rectangular upper part 13 of the desired height and width and an inwardly inclined tapered lower part 14 having a downwardly inclined narrow extension 15 projecting forwardly from the lower portion of the front of the side wall. The bottom edge of each side wall is formed of rear and front forwardly extending downwardly inclined edge portions 16, 17. The edge portion 16 is of less length than

and is disposed at a greater downward inclination than the edge portion 17. The rear wall 10 includes a rectangular upper part 18 of less height than the upper parts 13 of the side walls and an angle-shaped lower part 19 which is offset with respect to the part 18. The front wall 11 consists of an upper rectangular part 20 corresponding in height to the height of the parts 13 of the side walls, an inwardly inclined tapered intermediate part 21 and a forwardly directed downwardly inclined lower part 22. The bottom wall 12 consists of forwardly extending downwardly inclined rear part 23 and a forwardly extending downwardly inclined front part 24 of less inclination than and of greater length than the part 23. The forward edge of the latter is spaced from the rear edge of part 24 to form an opening 25 which communicates with the interior of the hopper. The parts 23, 24 are connected together by a combined coupler and supporting element 26 which depends from bottom wall 12. The element 26 is of angle form in cross section and includes a depending rearwardly inclined rear part 27 and an upwardly inclined forward part 28. The parts 27, 28 at their lower ends merge into each other. The part 27 at its upper end merges into the forward end of bottom part 23. The part 28 at its upper end merges into the rear end of the bottom part 24. The part 27 is formed with an opening 29 and an annular boss 30 on its rear face registering with opening 29. The element 26 extends from one side edge to the other side edge of bottom wall 12.

The lower end of the upper part 18 of the rear wall 10 aligns in spaced relation with the rear end of the rear part 23 of the bottom wall 12 to provide an opening 31 which communicates with the hopper. The lower part 19 of the rear wall 10 is formed with an upper rearwardly inclined part 32 and a forwardly extending downwardly inclined lower part 33. The lower end of part 32 and upper end of part 33 merge into each other. The upper end of part 32 merges into the lower end of the upper part 18 of said rear wall. The upper end of part 33 merges into the rear end of the part 23 of the said bottom wall. The ends of the rear wall part 19 align with the outer side of rear wall part 18.

The top wall 6 is secured to said side, front and rear walls. The rear wall is arranged between and secured to the side walls whereby the opening 31 and angle-shaped lower part 19 of the rear wall are closed at their ends. The front wall 11 is secured to and is of less height than the side walls. The bottom 12 is secured to the side walls, the latter are provided with depending portions 34 for closing the ends of opening 25 and said element 26.

The side, front and bottom walls are so formed and related to provide the lower end of the front of the hopper with an outlet opening 35 for the material. Secured to the front of the hopper and forming an outward continuation of the wall of opening 35 is a tapered discharge and directing spout 36 for the material to be placed.

There is secured to the upper face of the top wall 6 and bordering the sides of the opening 7 is a combined support, guide and abutment element 37, of rectangular form for a sliding gate 38 for controlling the opening 7. The element 37 borders the opening 7 and consists of a rear bar 39, a front bar 40 of less height than bar 39 and a pair of side bars 41, 42 corresponding in height to the bar 40 of and being of inverted

L-shaped in cross section. The bar 39 constitutes an abutment and the bars 41, 42 guides for the gate 38. The bars 40, 41, 42 form supports for the gate. The upper surfaces of the bars 40, 41, 42 are arranged below the upper surface of bar 39. The bars 41, 42 are oppositely disposed and have secured to the lower faces of their horizontal parts packing strips 43. The bar 40 is of inverted L-shape in cross section.

The gate 38 comprises a flat body part 44 having depending from the sides thereof a pair of oppositely disposed coupling parts 45 into which extend the horizontal parts of the bars 41, 42. The coupling parts are of L-shape contour in cross section and with the horizontal parts thereof bearing against the lower faces of said packing strips 43. The gate 38 is reciprocated for the purpose of closing and opening the intake or entrance. The means for reciprocating gate 38 will be hereinafter referred to.

The upper parts 13 of the side walls 7, 8 are formed with aligned openings 47 which communicate with the opening 31. Supported by the walls of the openings 47 is a nozzle element 48 termed an upper sweep. The element 48 extends outwardly at one end from the opening 47 in the upper part 13 of one side wall 7 and such upper part 13 has formed integral with its outer face an annular boss 49 forming an outward continuation of the walls of such opening 47. The element 48 extends outwardly from the boss 49.

Arranged in the opening 25 is a nozzle element 50 termed a lower sweep which has secured to and intermediate the ends of its bottom a feed pipe 51. The latter extends rearwardly through the opening 29 and the boss 30. The pipe 51 is projected rearwardly from the boss 39.

Suspended from the rear portion of the bottom wall 12 of the hopper by a pair of spaced vertical parallel hangers 51^a is a horizontally disposed cylinder 52 formed with axially apertured heads 53. Slidably mounted in and extending forwardly and rearwardly from said cylinder is an elongated bodily adjustable nozzle 54. The latter is slidably mounted in the heads 53 and is of a length to extend into the spout 36. The forward part 24 of bottom wall 12 is formed with an opening 55 in proximity to the opening 35. Integral at its forward end with the lower face of part 24 and registering with the opening 55 is a rearwardly directed horizontally disposed tubular member 56 formed with peripheral threads at its rear end. Connected to the rear end of member 56 is an axially apertured packing gland 57 carrying a packing 58 abutting against the rear end edge of member 56. The nozzle 54 passes forwardly through the gland 57, member 56 and opening 55. The wall of the latter in connection with the member 56 and gland 57 forms a support forwardly of the cylinder for the nozzle 54 intermediate the ends of the latter. The nozzle 54 has fixed thereto a piston 58 operating within the cylinder 52.

Extending forwardly from the upper portion of the front wall 11 and arranged above the top wall 6 is a horizontally disposed cylinder 59 having axially apertured heads 60, 61 and operating within the cylinder 59 is a reciprocatory piston 62 carried on one end of a piston rod 63. The latter extends rearwardly from cylinder 59, through the head 60 and it is connected to the gate 38. A bracing structure 64 is employed for cylinder 59 and such structure is secured to the hopper 5 and said cylinder.

Connected to and supported from one side of the hopper 5 is an inverted T-coupler 65 having its branches designated 66, 67 and 68. The branch 66 is to be connected to a compressed air supply, not shown. The branch 67 has connected thereto a pipe section 69 and the latter is attached at its upper end to the vertical branch 70 of a T-coupler 71. The horizontal branches of the coupler 71 are indicated at 72, 73. Attached to the branch 73 is a two-way 10 valve structure 74 formed with a handle 75 for operating it. Leading from the structure 74 and opening into the cylinder 59 through the head 61 is a flexible conducting line 76 for compressed air. Leading from the structure 74 and opening into the cylinder 59, through the head 61, is a flexible conducting line 77 for compressed air. The piston 62 and rod 63 are employed for controlling the operation of the gate 38, and the latter functions to control the opening and closing of the said entrance or intake opening 7. The cylinder 59, piston 62, piston rod 63, lines 76, 77 and structure 74 correlate to provide a fluid pressure operated means for controlling the opening and closing of the gate 38 with respect to the opening 7. Attached to the branch 72 of the coupling 71 is a one-way valve structure 78 which is also attached to a horizontal branch of a T-coupling 79 having its vertical branch indicated at 80 and its horizontal branches at 81, 82. The branch 82 is connected to the valve 78. Attached to the branch 67 of the T-coupling 65 is a two-way valve structure 83 and leading from the structure 83 and opening into the cylinder 52, through one of the heads of the latter, is a flexible conducting line 84 for compressed air. The structure 83 in connection with the lines 84, 85, cylinder 52 and piston 53 provide a compressed air operated controlling means for bodily adjusting the nozzle 54 with respect to the spout 36.

Attached to the branch 80 of the coupling 79 and opening into the rear end of the nozzle 54 is a flexible conducting line 88 for supplying compressed air to the nozzle 54. The lower end of the line 88 is connected to and opens into the rear end of the nozzle 54.

A pair of spaced aligned one-way valve structures are indicated at 89, 90 formed with handles 91, 92 respectively for opening their valves. The structure 89 is connected to the branch 81 of coupling 79. The structure 89 is also connected to a horizontal branch 93 of a T-coupling 94. The vertical branch 95 of coupling 94 has attached thereto a flexible line 96 for conducting compressed air to the nozzle element. The line 96 is connected to and opens into the pipe 51. The structure 90 is connected to the other horizontal branch 97 of the coupling 94 and it is formed with a lateral extension 98 which is attached to a flexible line 99 for conducting compressed air to the nozzle element 48. The line 99 is connected to and opens into the outwardly extending portion of said element 48.

The nozzle 48 is formed with narrow rectangular jets or ports 100 preferably three in number whereby the body of air delivered through each jet will be substantially of fan-like form. Preferably the size of each port 100 will be three by one-quarter of an inch. The nozzle 50 will be formed with a single jet or port 101 which will be narrow and of rectangular contour not to exceed the diameter of the nozzle. The body of air directed from nozzle 50 will be substantially of fan-like shape.

Compressed air may be supplied to the nozzle 54 independently of nozzles 48, 50, cylinder 59 and cylinder 52. All of the nozzles may have compressed air supplied thereto selectively whereby one nozzle may be made active independent of the other nozzles. Compressed air may be independently supplied to the cylinders 52, 59. When the nozzles 48, 50 are operated they are employed for removing material adhering to the front and sides of the hopper. The manner in which the lower portion of the sides and front of the hopper and the double inclination of the hopper bottom are arranged facilitates the travel of the material to be placed in a direction towards the spout.

What I claim is:

1. A compressed air operated placer comprising a hopper formed of a top having a controlled material intake, a front, a rear, a pair of sides and a bottom wall, said rear wall being of less height than said front wall, said front wall being formed in its lower portion with a mouth, said bottom wall extending forwardly at a downward inclination from said rear wall to said front wall, a spout forming an outward continuation of said mouth, a bodily adjustable controllable compressed air directing nozzle extending through said bottom into said spout, and a controllable compressed air operated means for adjusting said nozzle lengthwise with respect to the spout.

2. A compressed air operated placer comprising a hopper formed of a top having a controlled material intake at its top, a front, a rear, a pair of sides and a bottom wall, said rear wall being of less height than said front wall, said front wall being formed in its lower portion with a mouth, said bottom wall extending forwardly at a downward inclination from said rear wall to said front wall, a spout forming an outward continuation of said mouth, a bodily adjustable controllable compressed air directing nozzle extending through said bottom into said spout, and controllable compressed air operated means for adjusting said nozzle lengthwise with respect to the spout, said compressed air operated means being supported from said bottom.

3. A compressed air operated placer comprising a hopper formed of a top having a controlled material intake, a front, a rear, a pair of sides and a bottom wall, said rear wall being of less height than said front wall, said front wall being formed in its lower portion with a mouth, said bottom wall extending forwardly at a downward inclination from said rear wall to said front wall, a spout forming an outward continuation of said mouth, a bodily adjustable controllable compressed air directing nozzle extending through said bottom into said spout, controllable compressed air operated means for adjusting said nozzle lengthwise with respect to the spout, and a controllable sweep arranged in said bottom and directed towards said front.

4. A compressed air operated placer comprising a hopper formed of a top having a controlled material intake, a front, a rear, a pair of sides and a bottom wall, said rear wall being of less height than said front wall, said front wall being formed in its lower portion with a mouth, said bottom wall extending forwardly at a downward inclination from said rear wall to said front wall, a spout forming an outward continuation of said mouth, a bodily adjustable controllable compressed air directing nozzle extending through said bottom into said spout, controllable compressed air operated means for adjusting said

nozzle lengthwise with respect to the spout, and a controllable sweep arranged in said bottom and directed towards said front, said compressed air operated means being supported from said bottom.

5. A compressed air operated placer comprising a hopper formed of a top having a controlled material intake at its top, a front, a rear, a pair of sides and a bottom wall, said rear wall being of less height than said front wall, said front wall being formed in its lower portion with a mouth, said bottom wall extending forwardly at a downward inclination from said rear wall to said front wall, a spout forming an outward continuation of said mouth, a bodily adjustable controllable compressed air directing nozzle extending through said bottom into said spout, controllable compressed air operated means for adjusting said nozzle lengthwise with respect to the spout, and a controllable sweep mounted at the lower end of the rear wall and directed to said side walls.

6. A compressed air operated placer comprising a hopper formed of a top having a controlled material intake at its top, a front, a rear, a pair of sides and a bottom wall, said rear wall being of less height than said front wall, said front wall being formed in its lower portion with a mouth, said bottom wall extending forwardly at a downward inclination from said rear wall to said front wall, a spout forming an outward continuation of said mouth, a bodily adjustable controllable compressed air directing nozzle extending through said bottom into said spout, controllable compressed air operated means for adjusting said nozzle lengthwise with respect to the spout, and a controllable sweep mounted at the lower end of the rear wall and directed to said side walls, said compressed air operated means being supported from said bottom.

7. A compressed air operated placer comprising a hopper formed of a top having a compressed air controlled intake at its top, a front, a rear, a pair of sides and a bottom wall, said rear wall being of less height than said front wall, said front wall being formed in its lower portion with a mouth, said bottom wall extending forwardly at a downward inclination from said rear wall to said front wall, a spout forming an outward continuation of said mouth, a bodily adjustable controllable compressed air directing nozzle extending through said bottom into said spout, controllable compressed air operated means for adjusting said nozzle lengthwise with respect to the spout, each of said sides including an in-

wardly inclined tapered portion formed with a forwardly directed extension at its lower end, and said front including an inwardly inclined tapered portion terminated in a extension secured to the extensions of said sides, the inwardly inclined portion of said front being secured to the inclined tapered portions of said sides.

8. In a compressed air operated placer a hopper including a forwardly extending downwardly inclined bottom, a top provided with a material intake and a front formed with a mouth at its lower portion, a spout extending outwardly from said mouth for the discharge of the material, 10 a controllable compressed air operated means for controlling said intake, a controllable compressed air sweep supported from said bottom intermediate the upper and lower ends of the latter and directed towards said front, a controllable compressed air sweep disposed at the upper end of the latter and directed towards said front, and a controllable compressed air directing nozzle extending through the forward portion of said bottom into said spout.

9. In a compressed air operated placer a hopper including a forwardly extending downwardly inclined bottom, a top provided with a material intake and a front formed with a mouth, a spout extending outwardly from said mouth for the discharge of the material, a controllable compressed air operated means for controlling said intake, a controllable compressed air sweep carried by said bottom intermediate the front and rear of the latter and directed towards said front, 30 a controllable compressed air sweep carried by said bottom at the rear end of the latter and directed towards said front, a controllable compressed air directing nozzle extending through said bottom into said spout, and a controllable compressed air operated means for adjusting said directing nozzle lengthwise of said spout.

10. A compressed air operated placer including a hopper for receiving the material to be placed having a forwardly extending downwardly inclined bottom and a spout at the lower portion of its front for the discharge of the material therefrom, a controllable nozzle extending through the forward portion of said bottom into said spout for directing compressed air to expel the material from the hopper, and controllable upper and lower sweeps for respectively directing compressed air into the hopper from the upper end and from intermediate the ends of said bottom.

ROBERT O. HOWARD.
